PROTECTIVE HAND CUSHION

Walter J. Kanicki, 2011 3rd St.,
Bay City, Mich. 48706

Filed Apr. 4, 1974, Ser. No. 457,775

Term of patent 14 years

Int. Cl. D2—06

U.S. Cl. D2—361

FIG.1

FIG.2

FIG.3

FIG.4

FIG.5

FIG.6

FIG. 1 is a top plan view of a protective hand cushion showing my new design;

FIG. 2 is a bottom plan view thereof;

FIG. 3 is an end elevational view thereof as viewed in the direction of the arrows 3—3 of FIG. 1;

FIG. 4 is an end elevational view thereof as viewed in the direction of the arrows 4—4 of FIG. 1;

FIG. 5 is a side elevational view thereof as viewed in the direction of the arrows 5—5 of FIG. 1; and

FIG. 6 is a side elevational view thereof as viewed in the direction of the arrows 6—6 of FIG. 1.

I claim:

The new and ornamental design for a protective hand cushion, as shown.
